UNITED STATES PATENT OFFICE.

ADDI BENJAMIN CADMAN, OF BELOIT, WISCONSIN, ASSIGNOR, BY MESNE ASSIGNMENTS, TO STEWART-WARNER SPEEDOMETER CORPORATION, A CORPORATION OF VIRGINIA.

MACHINE FOR MAKING FLEXIBLE SHAFT-SHEATHINGS.

1,181,107.

Specification of Letters Patent.

Patented May 2, 1916.

Application filed August 18, 1910. Serial No. 577,353.

To all whom it may concern:

Be it known that I, ADDI BENJAMIN CADMAN, a citizen of the United States, residing at Beloit, county of Rock, State of Wisconsin, have made a certain new and useful Invention in Machines for Making Flexible Shaft-Sheathings, of which the following is a specification.

This invention relates to machines for making flexible shaft sheathings, and particularly a sheathing composed of coiled wires.

The object of the invention is to provide a machine, of the nature referred to, which is simple in construction, and efficient in operation.

Other objects of the invention will appear more fully hereinafter.

The invention consists substantially in the construction, combination, location, and relative arrangement of parts, all as will be more fully hereinafter set forth, as shown in the accompanying drawings, and finally pointed out in the appended claims.

Referring to the drawings, and to the various views and reference signs appearing thereon, Figure 1 is a view in front elevation of a machine embodying the principles of my invention. Fig. 2 is a view in side elevation of the same. Fig. 3 is a top plan view of the same. Fig. 4 is a broken detail view in top plan, the upper bending or coiling roll being removed, showing the arrangement and relation of the lower bending or coiling rolls and the coiling spindle. Fig. 5 is a fragmentary detail view showing the manner of coiling the wires to form the sheathing. Fig. 6 is a detail view of a coiling roll and its shaft. Fig. 7 is a broken detail, sectional view showing the coiling spindle on which the sheathing is coiled.

The same part is designated by the same reference sign wherever it occurs throughout the several views.

In carrying out my invention I propose to form a sheathing by continuously coiling two wires together, their respective coils being arranged in alternate relation with respect to each other, and preferably, though in this respect I do not desire to be limited or restricted, I employ wires of different sizes, the inside diameter of the coils of the smaller wire being less than the inside diameter of the coils of the larger wire. To

effect the desired result I bend the wires into coil form, the one in interlocking or alternating relation with respect to the other, and I progressively advance the successive coils and continuously feed the wires to the coiling devices under proper conditions of tension whereby the completed product is turned out in a continuous manner, and limited in length only by the length of the wires employed.

Many specifically different constructions and arrangements of devices may be employed for carrying my invention into practical operation. While, therefore, I have shown, and will now describe, one construction which I have found practical and efficient for the purpose, my invention, as defined in the claims, is not to be limited or restricted in its broadest scope to the particular form and arrangement shown.

In the embodiment disclosed in the drawings I employ a short spindle or mandrel on which the wires are coiled, the coiling of the wires thereon being accomplished by grooved rollers equally spaced around the spindle and suitably geared to rotate, and maintained under suitable pressure to accomplish the work required of them. I also place one or both of the wires under suitable feed tension. In practice, and in one embodiment of my invention, I place the smaller wire under considerable tension, which, however, may be adjustably regulated, and I also reduce the diametric size of that portion of the spindle or mandrel on which the smaller wire is coiled, as compared with that portion of said mandrel on which the larger wire is coiled.

Referring specifically to the construction shown in the drawings, numeral 10, designates a base plate, upon which are mounted the standards 11, 12. The standard 11, carries the bearing for the drive shaft 13, of the machine said shaft receiving rotary motion from any suitable or convenient source of power. The coiling spindle or mandrel 14, is removably mounted in the end of shaft 13, being held in place by a screw 15, or other equivalent means. This mandrel is provided with an enlarged portion 16, on which the larger wire coil is formed, and a reduced portion 17, on which the smaller wire coil is formed, the reduced portion 17, being at the extreme end of the mandrel.

Arranged in surrounding relation with respect to the mandrel to form a coiling space with the mandrel at the center thereof, are the coiling rolls 18, 19, 20. These rolls are shown as being equally spaced apart angularly with reference to the axis of the mandrel. The rolls are respectively carried by the shafts 21, 22, 23. The shafts 21, and 22, of the lower rolls 18, 19, are mounted at their ends in journal bearings formed in the standards 11, 12. The structures of these shafts and rolls are the same, one of them being shown in Fig. 6.

The upper roll shaft 23, is journaled at its ends in bearings formed in the arms of a bracket 24, pivotally mounted at their rear ends, as at 25, upon the standards 11, 12, or extensions thereof. The roll shafts are axially rotated in the same direction and at equal speeds. A simple arrangement of gearing for accomplishing this is shown wherein the main drive shaft 13, is provided with a drive pinion 26, intermeshed with equal sized pinions 27, 28, 29 on the roll shafts 21, 22, 23, respectively.

By mounting the roll shafts 21 and 22, in bearings in the standards 11, 12, said shafts are maintained in fixed relation, whereas the roll shaft 23, is mounted in a pivoted bracket or yoke 24, and therefore by rocking or swinging said yoke upwardly the roll 20 and its shaft 23, may be raised to permit access to the coiling spindle or mandrel 14, or the coils thereon.

The upper roll may be held yieldingly pressed downwardly toward the mandrel in any convenient manner. A simple arrangement is shown wherein a swing rod 30, is pivotally connected, as at 31, to a latch lever 32, the latter being pivotally mounted upon fixed parts of the standards, as at 33. The upper end of rod 30, is received in a lateral slot 34, in the free end of bracket 24, and a spring 35, is interposed between collars 36, 37, respectively bearing against the upper surface of bracket 24, and a nut 38, adjustably mounted on the threaded end of rod 30. The pivot axes 31, 33, of rod 30, and latch lever 32, are in such relation with respect to each other that they may be brought into vertical line, as seen in Fig. 1, thereby not only drawing the rod 30 endwise downwardly so as to cause the spring 35 to exert a desirable tension upon the upper roll bracket 24, but also locking the parts in this relation. By rocking the latch lever 32 upwardly the tension is relieved and the rod 30 is freed to permit the same to be released from the seat or slot 34, thereby releasing bracket 24, to permit the same to be rocked upwardly out of the way, carrying the upper roll 20, with it.

The larger wire, indicated at 39 is preferably, though not necessarily supplied to

the coiling spindle without any material degree of tension, that is, ordinarily, the tension imposed on this wire by merely drawing it from the supply reel is sufficient for all practical purposes, though in this respect 70 my invention, as defined in the claims is not to be limited or restricted, since varying degrees of tension may be desired or required according to varying conditions, requirements or characteristics of the 75 sheathing to be produced.

Ordinarily a considerable tension is required for the other wire 40. I have shown a simple arrangement of tension device for the purpose wherein the path of feed of 80 said wire leads between the series of lower tension rolls 41, and the upper tension rolls 42. Any desired number of these rolls may be employed according to the requirements, or any other suitable or equivalent tension 85 means may be employed. I have found that ordinarily three lower rolls 41, and two upper rolls 42, are sufficient, these being arranged, as shown, with the upper rolls 42 located above the spaces between each two 90 adjacent lower rolls. In order to adjustably regulate the degree of tension to be imposed upon the wire 40, the upper tension rolls are mounted in a slide plate indicated by dotted lines at 43, the height of 95 which may be varied by means of the adjusting screw 44, thereby varying the relative adjustment of the upper tension rolls relative to the lower rolls, and hence adjustably regulating the tension on the wire 100 which is fed between said rolls to the coiling mandrel.

In order to secure the desired progressive feed of the completed sheathing from the coiling mandrel, that is, the progression of the coils of the sheathing as the same are formed, I propose to feed the wire 39, to the coiling mandrel in a plane parallel with and next adjacent the end surface of the mandrel shaft 13, and any suitable or convenient means for progressing the coil, as it is formed, endwise of the mandrel may be employed. A simple arrangement is shown wherein the coiling rolls 18, 19, and 20 are peripherally grooved. One of these rolls, say the upper roll 20 is provided with a peripheral groove 45, in the vertical plane of the line of feed of the wire 39, and with regularly formed successive grooves of equal width corresponding to the size of the wire and equally spaced apart thereafter. The next roll, in the winding or coiling direction, say, for instance, roll 19, is also provided with peripheral grooves of the same width as the peripheral grooves of roll 20, and also equally spaced apart from each other, but the initial groove of said roll 19, is advanced a distance one third the transverse width thereof with reference to the initial groove of the top roll 20, that is, 110 115 120 125 130

a distance one third the diameter of the wire 39. Similarly the third roll 18, is grooved peripherally, but the initial groove thereof is advanced a distance equal to one third the diameter of the wire, with reference to the initial groove of the roll 19, or a distance of two thirds the diameter of the wire with reference to the initial groove of the top roll 20. It will be seen that this arrangement causes a continuous progressive advancement of the formed coils, as they are formed, longitudinally of the coiling mandrel, whereby as indicated in Fig. 3, the completed sheathing is continuously advanced or fed from the machine as the coils thereof are formed, and is limited in length only by the length of the wires employed.

While I have shown and above described one construction and arrangement for accomplishing the continuous feed of the completed sheathing from the machine other specifically different arrangements and constructions might equally well accomplish the desired result. In the broadest scope of my invention, as defined in the claims, therefore, I do not desire to be limited or restricted in respect to the specific form of advancing means for the completed sheathing.

The smaller wire 40, as above stated, is preferably though not necessarily, coiled to a somewhat smaller diameter of coil than that of the larger wire. Where the smaller wire is coiled to a smaller diameter of coil than the larger wire I prefer to reduce the diameter of the coiling mandrel, as indicated at 17, at the point where the smaller wire coils are formed, and at this point I omit the grooves in the peripheries of the coiling rolls 18, 19, 20, and also slightly reduce said rolls in external diameter, as indicated at 48, Fig. 5, thereby permitting sufficient clearance for the larger wire coils when the smaller wire coils are formed and forced between them, as clearly shown. The increased tension imposed on the smaller wire, as above explained, enables the smaller wire coils to be formed and forced between the larger wire coils, while the continuous advancing feed of the larger wire coils as they are formed will also carry along with them the interlocked smaller wire coils.

By the arrangement of mechanism above described I am enabled to employ a short coiling mandrel and to readily remove and replace the same as occasion may require.

In order to start up the machine the feed-in end of the larger wire is first preliminarily and initially coiled into several turns as a starting coil. This starting coil is then slipped endwise over the coiling mandrel, the upper roll, meanwhile being raised out of the way. The smaller wire is then led into proper position and coiled at its end

into one or more convolutions, as shown in Fig. 5. The upper roll bracket is then lowered and locked, and the machine started up, that is, rotation is imparted to the shaft 13, the wires being drawn from conveniently arranged reels arranged to pay out the wires in the proper manner as required by the machine, while the completed article feeds continuously off the end of the mandrel, the desired looseness or tightness of the coils being regulated by regulating the tension on the wires.

Where the rolls 18, 19, 20 are of greater diameter than the coiling mandrel 17, or of the coils formed thereon, and hence travel at a greater peripheral speed of the coils, then the resulting slip of the peripheral surfaces of the said rolls upon the outer surface of the convolutions of the wire will exert a spinning effect tending to stretch or draw out the metal of the wire convolutions thereby aiding in the coiling operation not only to form the convolutions but also to distribute the strains produced by the coiling operation thereby tending to set the coil and to prevent appreciable tendency of the convolutions to expand. Any such spinning action as above referred to would be dependent, obviously, upon a rate of peripheral speed of the rolls 18, 19, 20, greater than that of the convolutions of the coil, and, this, of course would depend upon the ratio of gearing employed to drive the rolls and the mandrel. Should the coil slip to any extent, on the coiling mandrel, however, this spinning action would be correspondingly decreased. These are all theoretical details which may safely be left to the mechanic in constructing the machine.

Having now set forth the object and nature of my invention, and a construction embodying the principles thereof, and having described such construction, its purpose, function, and mode of operation, what I claim as new and useful and of my own invention, and desire to secure by Letters Patent is,—

1. In a machine for making flexible sheathing, a coiling mandrel, means for continuously coiling two wires into coils of relatively different diameters upon said mandrel, with the coils of one wire having its convolutions in alternating and partially interposed relation to the respectively adjacent convolutions of the other wire, one of said wires being smaller in size than the other, and means for imposing an adjustable tension upon the feed of the smaller wire.

2. In a machine for making flexible sheathing, a coiling mandrel, means for continuously coiling two wires upon said mandrel with their coils of relatively different diameters and in alternating partially interposed relation, the one inside the other, one of said wires being of smaller diameter

than the other, and means for imposing an adjustable tension upon the wire of smaller diameter.

3. In a machine for making flexible sheathing a coiling mandrel having an enlarged portion and a reduced portion, means for coiling two wires, one upon each of said portions with the coils of one wire inside those of the other and having their convolutions respectively in alternating and partially interposed relation, and means for imposing a tension upon the feed of the wire coiled upon the reduced portion of said mandrel.
- 15 4. In a machine for making flexible sheathing, means coöperating to coil two wires into coils of relatively different diameters, the one inside the other, with the convolutions of the inner coil partially interposed between those of the outer coil, the coil forming means constructed to feed the formed coils from the machine.
- 25 5. In a machine for making flexible sheathing, means for coiling two wires into coils of relatively different diameters, the one inside the other, with the convolutions of the inner coil extending partially into the space between those of the outer coil, means for imposing a tension on one of said wires, the coiling means operating to feed the formed coils from the machine.
- 30 6. In a machine for making flexible

sheathing, means coöperating to coil two wires into interlocking coils of relatively different diameters, the one inside the other 35 with the convolutions of the inner coil extending partially into the space between those of the other coil, and means to impose a tension upon one of said wires while being formed into a coil, the coiling means 40 operating to feed the formed coils from the machine.

7. In a machine for making flexible sheathing, a coiling mandrel having an enlarged portion and a reduced portion, means 45 for simultaneously coiling two wires, one upon each of said portions with the convolutions of said coils in alternating and partially interposed relation, the one coil inside the other, means for applying to the 50 wires supplied to said mandrel portions relatively different tensions, the coiling means operating to feed the coils endwise from the end of the mandrel as they are formed.

In testimony whereof I have hereunto set my hand in the presence of the subscribing witnesses, on this 25th day of July, A. D., 1910.

ADDI BENJAMIN CADMAN.
